DESIGN FOR A TEXTILE FABRIC OR SIMILAR ARTICLE

Barney Rosenbloom, New York, N. Y.

Application August 9, 1935, Serial No. 58,035

Term of patent 3½ years

To all whom it may concern:

Be it known that I, Barney Rosenbloom, a citizen of the United States, residing at New York, county of Bronx, and State of New York, have invented a new, original, and ornamental Design for a Textile Fabric or Similar Article, of which the following is a specification, reference being had to the accompanying drawing, forming a part thereof.

The figure shows a plan view of a textile fabric embodying the design, the repeat unit of the design being outlined by the dot and dash lines, which unit is repeated in the relationship indicated by the extensions beyond the unit boundaries.

The design comprises an arrangement of relatively broad and narrow substantially rectangular spaces and relatively smaller substantially rectangular spaces, some of the spaces being made up of a series of slanting alternate stripes of different shades or colors and others of the spaces being of one shade or color throughout, an example of a relative general layout and of relative general proportions of the various types of spaces being shown for purposes of illustration in the accompanying drawing of an embodiment of the design.

I claim:

The ornamental design for a textile fabric or similar article, substantially as shown and described.
